UNITED STATES PATENT OFFICE.

GEORGE W. BAKER, OF WILMINGTON, DELAWARE.

LEATHER-STAKING MACHINE.

SPECIFICATION forming part of Letters Patent No. 394,750, dated December 18, 1888.

Application filed September 27, 1888. Serial No. 286,619. (No model.)

To all whom it may concern:

Be it known that I, GEORGE W. BAKER, a citizen of the United States, and a resident of Wilmington, in the county of New Castle and State of Delaware, have invented certain new and useful Improvements in Leather Staking and Softening Machines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a side view of the machine. Fig. 2 is a plan view of the same. Fig. 3 is a detail of the pedal. Fig. 4 is an enlarged view of the rollers. Fig. 5 is a transverse section showing the bridge.

This invention has relation to machines for staking and softening leather; and it consists in the construction and novel combination of devices, as hereinafter set forth.

The invention relates to certain improvements upon a leather-staking machine for which Letters Patent No. 372,507 were granted to me on the 1st day of November, 1887; and the object of the improvements is not only to facilitate staking and softening large and heavy skins, but also to perfect the staking and softening operation.

In the accompanying drawings, the letter A designates the main frame of the machine, having guides a at its ends for the table-frame B, which is capable of vertical reciprocation. The frame B is formed with a longitudinal bar, C, supported by sliding uprights b, engaging the guides a, and also carrying the upright arms c, which slide in ways a' of the longitudinal bar D of the main frame. The table-wings E E are attached to supports of the bar C and extend longitudinally, a longitudinal slot or guideway, b', between said wings serving to receive the long slide F, which has its upper surface flush with the surface of the table, as shown, so that it forms a part of the working-surface on which the skin is placed. The table is in this manner made large enough to accommodate large and heavy skins.

G is a holding-bridge, which extends across the slot b' between the wings of the table, at about its middle portion, and allows the slide F to reciprocate freely below said bridge, which is of little height, and is formed with beveled ends and rounded edges, so that the skins can be moved over it with facility. The slide F is made long enough to fill the slot on both sides of the bridge, so that the skin cannot get into said slot to be caught thereby, or to interfere in any manner with its smooth and ready passage over the surface of the table in any direction under the manipulations of the operator.

H is a holding jaw-slide, which operates, in connection with the bridge, to hold the skin at any point desired as such part is brought over the bridge-jaw G. The movement of the jaw-slide is automatic, it being connected to a crank-arm, c', of a rock-shaft, d. The jaw-slide works in a guide, d', and the rock-shaft d is also provided with a short crank-arm, e, having a wrist-pin, f, adapted to engage a notch, n, in the reciprocating pitman g, which is operated by a cam, h, on the main shaft K of the drive-wheel W. A spring, h', attached to the pitman, serves to hold the jaw down to its work with elastic force, the cam acting to raise the jaw from the skin to permit it to be moved. A second spring, g', connects the wrist-pin F to the main frame, and is designed to throw it out of the notch n when the pitman is raised. At the same time the rock-shaft, being relieved from its connection with the pitman and its spring, is acted upon by this secondary spring, this stop-motion being designed to raise the holding-slide H and to hold the same in raised position until it is desired to put the jaw in operation again. This is effected by a slight pressure on the jaw, which moves the crank-arm e a little back, so that it engages the notch of the pitman.

The main wheel W is provided with a pitman, J, which is connected to the carrier L, to which the staking-tool S is attached, and as the wheel W is turned the carrier L reciprocates and communicates a like reciprocating motion to the long slide F, which is connected thereto by the arm K. The staking-tool carrier travels on the guide N, which is connected to the vertically-reciprocating frame Z, which is moved by the action of the twin rock-shafts

C' C' and the front and rear cams B' B', said rock-shafts being connected to each other and to a crank-arm of the main driving-shaft.

- 5 The long slide F is provided with a transverse slot, l, below the staking-tool, and in said slot are located the steel transverse rollers m m, the upper peripheries of which are about flush with the surface of said slide.
- 10 When the staking-tool descends, its blade or knife t presses the leather so as to bend it over the rollers downward between their upper portions, and in this manner, as the staking-tool is operated, a rolling pressure is applied on the under or grain side. These rollers are also important in preventing alum-tanned or stretchy skins from bagging up under the knife.
- 15 In front of the staking-tool is provided the clearer V, which consists of a wide blade, v, having rounded edges and carried by a foot, P, having a stop, s, and a tension or pressure spring, l'. The blade v is held between the face of the foot and the clamp m' by the bolts 20 n', passing through slots of the blade, which is made adjustable in order that its pressure may be regulated to suit the work. The blade v presses on the work just above the outer roller, so that the work is operated between 25 this roller and the blade v. In this manner a little friction is put on the roller and the device serves an important purpose in stretching or clearing the skin in front of the staking-tool.
- 30 The table, and with it the long slide, can be moved by means of the pedal-frame I, which is pivoted to the end portions of the main frame, and is provided with lever-arms which extend under the supports b of the table-frame B.

The operation is as follows: The skin of leather being placed upon the table between the jaw and holding-bridge is held thereby, while the clearer and staking-tool and the rollers below act to stretch and bend the skin in the manner designed. When the holding-jaw is raised during the reverse motion of the long slide, the skin is shifted by the operator to obtain a fresh purchase for the work over 45 a new portion thereof, and when the jaw has closed down the long slide and the carrier of the staking-tool and clearer move away from the holding-clamp, clearing the path of the staking-knife, and bending the skin in said 50 path between the rollers by the action of said knife.

Having described this invention, what I claim, and desire to secure by Letters Patent, is—

- 60 1. In a leather-staking machine, the combi-

nation, with a longitudinally-slotted table and a transversely-slotted slide reciprocating in the slot of said table, of the rollers in the slot of the slide, a staking-tool, and reciprocating mechanism, substantially as specified. 65

2. In a leather-staking machine, the combination, with the slotted table and bridge, of the long slide reciprocating beneath the bridge and a reciprocating staking-tool, substantially as specified. 70

3. In a leather-staking machine, the combination, with the slotted table and bridge-jaw, of the vertically-reciprocating jaw-slide, the longitudinally-reciprocating transversely-slotted slide, and the staking-tool having vertical as well as longitudinal motion of reciprocation, substantially as specified. 75

4. The combination, with a reciprocating leather-staking tool and a transversely-slotted slide reciprocating therewith, of the rollers in the slot of said slide and the spring-actuated clearer in front of the staking-tool, substantially as specified. 80

5. A machine for staking leather having a slotted table and bridge-jaw, a transversely-slotted slide reciprocating in the slot of the table, rollers in the slot of the slide, and a clearer in front of the staking-tool, substantially as specified. 85

6. In a leather-staking machine, the combination, with the notched pitman, the staking-tool, and the slide-jaw, of the rock-shaft and its crank-arms, the main spring of the pitman, and the secondary spring connected to one of the arms of the rock-shaft, substantially as 90 specified.

7. A leather-staking machine having a longitudinally-slotted table having a surface-extension on each side of its slot, a bridge-jaw spanning its slot, a reciprocating transversely-slotted slide in the slot of the table, and a reciprocating staking-tool, substantially as 95 specified.

8. A leather-staking machine consisting of a main frame having a slotted vertically-reciprocating table and a pedal-frame, a tool-carrier frame having a vertical reciprocating mechanism, a transversely-slotted reciprocating slide, a bridge-jaw over said slide, a reciprocating staking-tool carrier, an arm connecting said slide and tool-carrier, a slide-jaw operating in connection with said bridge-jaw, and operating mechanism, substantially as 105 specified.

In testimony whereof I affix my signature in 110 presence of two witnesses.

GEORGE W. BAKER.
